UNITED STATES PATENT OFFICE.

GEORGE M. PORTEOUS AND FREDERICK S. MILLER, OF CHICAGO, ILLINOIS.

DESIGN FOR A PHOTOGRAPH-EXHIBITOR-CASE BODY.

SPECIFICATION forming part of Design No. 18,871, dated January 15, 1889.

Application filed December 17, 1888. Serial No. 293,887. Term of patent 7 years.

To all whom it may concern:

Be it known that we, GEORGE M. PORTEOUS, a citizen of the United States, and FREDERICK S. MILLER, a subject of the Queen of Great Britain, both residing at Chicago, in the county of Cook and State of Illinois, have invented and produced a new and original Design for a Photograph-Exhibitor-Case Body, of which the following is a specification, reference being had to the accompanying drawing, forming part thereof.

The drawing represents in elevation a photograph-exhibitor-case body embodying our design, the lid or cover being absent or understood to be thrown back out of sight, since it forms no portion of our present design.

The leading feature of our design consists in the substantially half-elliptic or half-oval form of a photograph-exhibitor-case body, which said feature is shown in the accompanying drawing, and further shown in mechanical Letters Patent, No. 379,522, granted to us March 13, 1888.

In the said drawing, A indicates the substantially half-elliptic or half-oval shaped photograph-exhibitor-case body, and a the frontside thereof. Upon the side a is a raised rib or head, a', arranged concentric and in harmony with the curved edge a² of said side, and within the space that is bounded by the rib a', and the top edge portion a³ of said side is a raised substantially half-elliptic or half-oval shaped figure, a⁴, which is in harmony with the substantially half-oval outline of the side a of the case-body. 35

What we claim is—

The design for a photograph-exhibitor-case body, consisting of the substantially half-oval-shaped case-body A, substantially as shown and described.

GEORGE M. PORTEOUS.
FREDERICK S. MILLER.
